United States Patent Office.

WILLIAM HULL AND CHARLES W. HAMMOND OF BALTIMORE,
MARYLAND.

Letters Patent No. 95,351, dated September 28, 1869.

GRAIN-DRIER.

The Schedule referred to in these Letters Patent and making part of the same.

To all whom it may concern:

Be it known that we, WILLIAM HULL and CHARLES W. HAMMOND, of the city and county of Baltimore, and State of Maryland, have invented a new and improved Grain-Sweater, Dryer, and Cleaner; and we do hereby declare that the following is a full, clear, and exact description of the construction and operation of the same, reference being had to the accompanying drawings, making a part of this specification, in which—

Figure 1 is a vertical cross-section through line *y y* of fig. 2.

Figure 2 is a longitudinal vertical section through line *x x* of fig. 1.

This invention relates to that class of machines for cleaning grain, &c., in which a hollow rotating cylinder is employed, provided with oblique or "worm" flanges, partitions, or deflectors for moving the grain longitudinally with the cylinder, as the latter rotates; and

Our improvement consists in the employment, in connection with such cylinder, of another surrounding cylinder or cylinders, having oblique deflectors, inclined in the opposite direction to those of the inner cylinder, and so constructed, that when the grain has been moved the whole length of the inner cylinder, it will escape therefrom, and fall into the next outer one, and therein travel back to the point where it was first introduced into the machine, and so on, from cylinder to cylinder, till it is perfectly cleaned and dried.

In connection with this arrangement of cylinders and oblique deflectors, we employ a peculiar arrangement of sieves or screens, to screen off the dust, &c., from the grain, as it travels along from end to end of the machine. And outside of all the working-cylinders above referred to, we place a hollow shell, or double-wall cylinder or jacket, through which hot air, steam, or other heating-agent is passed, in order to dry and sweat the grain subjected to the cleaning and polishing-operation within the enclosed cylinders.

In the drawings—

F is the supporting-frame, and *S* is the working-shaft, which carries and rotates the several cylinders at once.

A is the inner cylinder, receiving the grain from a hopper at its left-hand end, fig. 2, where it is open at its centre, and, when rotated, conveying the grain along to its opposite end, by means of oblique "worm," or "screw"-shaped deflectors, *a a a*, forming between them a spiral passage, along which the grain travels.

When the grain arrives at the right-hand (fig. 2) end of this cylinder, it falls out, and is caught in an enclosing-cylinder, *B*, and by this cylinder conveyed back to the left-hand end of the machine, by means of spiral or oblique deflectors, *b b b*, arranged in a direction opposite to that of the deflectors *a a a*.

As it travels back to its starting-point between the deflectors *b b*, it is sieved or screened, by means of wire sieves or foraminated plates, *c c c*, forming the floor on which it moves, the dirt dropping through the sieves into the space *e*, and travelling along to the end of the cylinder directly under the grain.

The grain is discharged at *C* into a suitable receptacle, and the dirt at *E* into another.

Around these cylinders is the steam or hot-air space *G*, into which the steam, air, or other heating-agent is introduced at any suitable point, and from which also it may be removed wherever most expedient.

If steam is employed, suitable drip-pipes or cocks may be arranged along its under edge.

The heating-jacket or cylinder *G* is not rotatory, being supported on its own frame.

The jacket may be so constructed that either steam or hot air may be employed, at pleasure. Suitable doors may be provided for the purpose of opening the cylinders, to clean them, &c. They may, for this purpose, be constructed in longitudinal segments of any suitable size.

It is evident that we need not be restricted to two conveying-cylinders, carrying the grain once back and forth, as shown in the drawing, but any convenient and practicable number might be used, the inner one always emptying at one end into that next enclosing it.

By the process herein described, the grain is not only cleaned and polished, but, at the same time, it is thoroughly sweated and dried, so that it will keep for almost any length of time.

Having thus described our invention,

What we claim as new, and desire to secure by Letters Patent, is—

The screen *c*, combined with the enclosing-cylinder *B*, dirt-space *e*, and spiral flanges *b*, substantially as and for the purpose set forth.

WILLIAM HULL.
CHAS. W. HAMMOND.
